UNITED STATES PATENT OFFICE

2,156,501

CELLULOSIC RIBBON

Morris Katz, Bronx, N. Y.

Application December 8, 1937, Serial No. 178,766

14 Claims. (Cl. 41—21)

This invention relates to the production of what is termed cellulose sheets, tape or ribbon preferably made from such transparent or translucent materials as, for example, Cellophane; and the object of the invention is to provide a product of manufacture of the character described made in accordance with my improved method, which consists in printing or otherwise applying markings, of predetermined character 5 or design, to an elongated strip or sheet of Cellophane longitudinally of or at longitudinally spaced intervals thereon and then in folding the strip or sheet to produce predetermined longitudinally arranged and spaced markings having 10 deep or varied depth color values throughout the strip or sheet so as to produce pleasing and ornamental effects in the resulting product; and with these and other objects in view, the invention consists in a ribbon or tape of the character 15 hereinafter more fully described and claimed.

The invention is fully disclosed in the following specification, of which the accompanying drawing forms a part, in which the separate parts of my improvement are designated by suitable reference characters in each of the views, and in which:

Fig. 1 is a diagrammatic view illustrating one method of marking a strip according to my invention.

Fig. 2 is a face view of a marked strip illustrating a method of folding the same to form the resulting ribbon or strand.

Fig. 3 is an elongated sectional view on the line 3—3 of Fig. 2.

Fig. 4 is a view similar to Fig. 2 showing a modified form of marking.

Fig. 5 is a face view of a part of a strip showing a modified form of marking thereon.

Fig. 6 shows the strip of Fig. 5 partially folded.

Fig. 7 is a section on the line 7—7 of Fig. 6.

Fig. 8 is a view showing the final fold of the strip shown in Figs. 5, 6 and 7.

Fig. 9 is a section on the line 9—9 of Fig. 8.

Fig. 10 is a view similar to Fig. 5 showing a modification.

Fig. 11 is a view similar to Fig. 8 showing the strip of Fig. 10 completely folded.

Fig. 12 is a view similar to Fig. 2 showing another method of marking and also illustrating a different method of folding the strip.

Fig. 13 is a view similar to Fig. 12 showing another modification, and

Fig. 14 is a view similar to Fig. 12 showing another modification.

For the purpose of illustrating one method of

carrying my invention into effect, I have diagrammatically illustrated in Fig. 1 of the drawing a part of an apparatus which may be used in the application of markings at longitudinally spaced intervals on a Cellophane strip, which markings may be of any desired depth of color but are usually in the form of tints or light prints of a given color. In the drawing 10 represents a part of a roll of strip Cellophane 11 supported adjacent a printing or tinting mechanism 12. This mechanism includes an ink fountain 13 in which ink of the desired color is placed for transfer onto the strip 11. A printing roller 14 having printing surfaces 14a thereon, receives its inking through ink transferring rollers 13a. The strip 11 is guided through the mechanism 12 by rollers 15, 15a so as to expose the strip 11 to the printing surfaces 14a to receive the desired imprint thereon which is governed by the arrangement and structure of the surfaces 14.

The roller 15 is preferably mounted in connection with one end of a lever 16 pivoted to the mechanism 12 as seen at 17. The lever 16 includes an upwardly directed part 18 to which is pivoted a lever 19, one end 20 of which extends upwardly, and pivoted to said end is a link 21. The other end 22 of the lever 19 has a cross member 23 around which the strip 11 passes as it leaves the mechanism and prior to entering any suitable folding mechanism which may be provided.

Secured to and projecting above the unit 12 is a rod 24 on which is slidably mounted a block 25 to which the free end of the link 21 is pivoted. The block 25 operates upon a coil spring 26 arranged on the rod 24 in its upward movement. Upon the upper end of the rod 24 is an adjustable collar 27 forming a stop for the spring 26 and by means of which the tension of the spring may be adjusted. Another adjustable collar 28 is also arranged on the rod 24 to limit the downward movement of the block 25. With this construction the desired tension on the strip 11 may be regulated in its passage through the printing mechanism and in its discharge from said mechanism.

In Figs. 2 and 3 of the drawing is shown the strip 11 characterized by the mechanism as diagrammatically illustrated in Fig. 1, the printing surfaces 14a applying transverse markings 29 on the strip 11 at longitudinally spaced intervals, these markings being of one color and contrasting to the color of the strip 11, which in some instances may be of transparent structure rather than of a given color. The strip 11 is 55

then folded to bring side edge portions 39, 40 thereof one upon the other on the central portion 32 of the strip so that the markings 29 which are in the form of tints as they would appear in the extended position at the left of Fig. 2, are in deeper color values as they would appear in the transverse bars 29a at the right of Fig. 2 by reason of arranging the tints one upon the other. Assuming that these tints are blue and that the strip is of the colorless or transparent structure, the resulting ribbon or strand will have spaced blue markings thereon which are spaced apart by the blank or unprinted portions of the strip.

In Fig. 4 of the drawing a slight modification 15 of the structure shown in Figs. 2 and 3 is shown wherein the strip may be passed through the mechanism shown in Fig. 1 of the drawing twice instead of once, or passed through two similar mechanisms for the application of two different colored tints or markings on the strip 11a. 20 For example, the blue markings 29 may first be applied to the strip 11a as in Fig. 2 of the drawing and then red markings 33 will be applied to the strip adjacent the markings 29 so that the resulting ribbon or strand will have an arrangement of red, and what may be termed white, and blue bars extending transversely of the ribbon continuous throughout the length thereof, the white being given the effect of white 30 by the translucency of the strip and especially when arranged upon a white paper wrapping in the use of the ribbon for tying purposes. In this connection it will be understood that the product may be used for any desired purpose as a 35 means of trimming or wherever ribbons or strands of this type could be used. It will also appear that any number of colors may be arranged on the strip as well as any type or kind of colors to produce multi-color effects.

It will also appear that the prints or other 40 markings may be of any desired outline or contour or may be so arranged as to form shaded effects in the resulting ribbon or strand, and in this connection I have shown in Figs. 5 to 9 inclusive a strip 11b having an irregular tint or 45 marking thereon of one color as shown at 34, that is to say, a marking which includes a portion 34a completely transversing the strip, a portion 34b terminating short of the said edges of 50 the strip and a portion 34c arranged centrally of the strip. It will thus be seen that by folding the strip shown in Fig. 5 in the manner illustrated in Figs. 6, 7, 8, and 9 the various sections 34a, 34b and 34c will produce a shaded effect of a single color longitudinally of the strip, 55 the section 34a being darker than the section 34b whereas the section 34c is lighter than the section 34b. By spacing the prints or markings 34 one from the other as seen in Fig. 5, a blank or 60 unmarked section 35 will appear between the sections 34a and 34c.

With the structure in these figures, it will appear from a consideration of Fig. 9 of the drawing that the section 34a will have a depth of 65 color equal to the compiled five layers of the strip 11a arranged one upon the other when the strip is completely folded as seen in Figs. 8 and 9, whereas the section 34b will have a depth of color equal to the three thicknesses of the strip, 70 and the section 34c will have the color value of the single sheet thickness, or in other words, equivalent or substantially equivalent to the original tint or shade of the marking 34.

In Figs. 10 and 11 of the drawing I have shown 75 at 11c a strip provided with spaced markings 36

which differ from the markings 34 simply in extending the shaded sections to both sides of a central deep color section so that the resulting strip will have shaded sections extending at either side of a central deep shaded section, for example, the section 36a in Fig. 11 of the drawing, at each side of which are lighter shaded sections 36b beyond which are the still lighter sections 36c. Here again the markings 36 are spaced apart so as to form the blank or spacing sections 37 between the light tint sections 36c. It will of course be understood that the marked sections may also blend one with the other on the resulting ribbon or strand as with the structure shown in Fig. 4 of the drawing. Adjacent 15 or alternate markings 36 may be of different colors so as to produce varied color and shaded color effects longitudinally of the ribbon. This is also true of the structure shown in Figs. 5 to 20 inclusive.

It is of course not essential to apply markings or prints to a strip to entirely transverse the strip. For example, in Fig. 12 of the drawing I have shown a strip 11d with prints or markings 38 arranged at longitudinally spaced intervals 25 at opposite side edge portions 39, 40 of the strip 11d so that in folding said edge portions inwardly upon the strip as seen at the right of Fig. 12, each marking will be folded upon itself to form deeper shades or color values in the resulting markings 38a as they appear on the finished ribbon or strand.

In the construction shown, the side edges 39 and 40 are formed into a single fold but it will be apparent that any number of folds may be 35 produced depending upon the color effect desired in the resulting ribbon. With this construction, the central portion 41 of the ribbon will remain transparent or of the color of the strip 11d as a whole, as will also the intermediate spacing sections 42.

In Fig. 13 is shown a strip 11e which differs from the strip 11d insofar as the prints or markings are concerned simply with the arrangement of the markings 38 on the side edge portions 39 45 and 40 of the strip. That is to say, in this later construction the markings 38a on the edge 39 are staggered in relationship to the markings on the edge 40 instead of being in alignment therewith as in Fig. 12, thus producing a staggered arrangement of the markings 38a on the side edges of the resulting folded strip as seen at the right of Fig. 13.

In Fig. 4 I have shown at 11f a strip having circular markings 43 arranged at the side edge 55 portions 44 and 45 of the strip instead of the rectangular markings 38 as in Figs. 12 and 13, so that in folding the edges 44 and 45 inwardly as seen at the right of Fig. 14, the resulting deeper toned or shaded markings 43a will be 60 semicircular or semispherical in form to produce scallop-like edgings to the side edges of the resulting ribbon or strand.

It will of course be apparent that the illustrations in the accompanying drawing are only a 65 few of the innumerable combinations and effects that could be produced in premarked or printed cellulosic sheets or strips later folded to produce in the resulting folded strip, various kinds and classes of effects, color values, as well as the 70 shaded effects. It will also appear that the contour or shape of the markings and the resulting characteristics as appearing on the sheet, ribbon, tape or strand may be produced in many shapes and forms to produce characters, sym- 75

bols or marks of identification which will be appropriate for the many uses for which the sheet, ribbon or strand may be used.

In referring to strip or ribbon it will be understood that this may define a relatively wide strip of material which can be cut up into sheets of a width equal to the width of the resulting strip or ribbon and of any desired length. These sheets or bands may be used in wrapping or otherwise decorating packages of various kinds and classes.

Having fully described my invention, what I claim as new and desire to secure by Letters Patent, is:

1. A product of the class described comprising a folded strip of cellulosic material, said strip having markings spaced longitudinally thereof, said markings being of a color contrasting to the color of said strip and produced in color depth values controlled by the longitudinal folding of said strip to arrange transverse portions of markings one upon the other.

2. A product of the class described comprising a folded strip of cellulosic material, said strip having markings spaced longitudinally thereof, said markings being of a color contrasting to the color of said strip and produced in color depth values controlled by the longitudinal folding of said strip to arrange transverse portions of markings one upon the other, and the markings being so arranged on the strip with respect to the folds thereof as to produce on the resulting folded strip shaded effects of a given color.

3. A product of the class described comprising a folded strip of cellulosic material, said strip having markings spaced longitudinally thereof, said markings being of a color contrasting to the color of said strip and produced in color depth values controlled by the longitudinal folding of said strip to arrange transverse portions of markings one upon the other, the markings being so arranged on the strip with respect to the folds thereof as to produce on the resulting folded strip shaded effects of a given color, and the shaded effects extending in opposite directions longitudinally of the resulting folded strip from a central point in each marking.

4. A ribbon-like product of the class described comprising a folded strip of cellulosic material, said strip having markings spaced longitudinally thereof, said markings being of a color contrasting to the color of said strip and produced in color depth values controlled by the longitudinal folding of said strip to arrange transverse portions of markings one upon the other, and alternate markings on the strip being of different colors to produce multiple color markings longitudinally of the resulting ribbon.

5. A ribbon-like product of the class described comprising a folded strip of cellulosic material, said strip having markings spaced longitudinally thereof, said markings being of a color contrasting to the color of said strip and produced in color depth values controlled by the longitudinal folding of said strip to arrange transverse portions of markings one upon the other, alternate markings on the strip being of different colors to produce multiple color markings longitudinally of the resulting ribbon, and respective groups of markings arranged longitudinally of the resulting ribbon being spaced apart by the base or ground color characteristics of the strip from which the ribbon is formed.

6. A ribbon-like product of the class described comprising a folded strip of cellulosic material,

said strip having markings spaced longitudinally thereof, said markings being of a color contrasting to the color of said strip and produced in color depth values controlled by the longitudinal folding of said strip to arrange transverse portions of markings one upon the other, and the markings on the resulting ribbon being arranged upon predetermined portions of the transverse sections of the ribbon.

7. A product of the class described comprising a folded strip of cellulosic material, said strip having markings spaced longitudinally thereof, said markings being of a color contrasting to the color of said strip and produced in color depth values controlled by the longitudinal folding of said strip to arrange transverse portions of markings one upon the other, and the markings on the resulting ribbon being disposed at side edge portions only thereof.

8. A product of the class described comprising a folded strip of cellulosic material, said strip having markings spaced longitudinally thereof, said markings being of a color contrasting to the color of said strip and produced in color depth values controlled by the longitudinal folding of said strip to arrange transverse portions of markings one upon the other, the markings on the resulting ribbon being disposed at side edge portions only thereof, and the markings on one side edge of the ribbon being staggered with respect to the markings on the other side edge thereof.

9. An article of merchandise of the class described comprising a sheet of cellulosic material, said sheet having tint-like color value markings on predetermined sections or areas thereof in a color contrasting to the color of the sheet, and the sheet being folded to dispose one part of the marked sections or areas of the sheet upon the other part of said sections or areas so as to reproduce in the resulting product colored markings having deep color values.

10. The herein described method of forming characterized cellulosic ribbon which consists in providing an elongated strip of cellulosic material, applying characterized markings on the strip at longitudinally spaced intervals, then folding the strip longitudinally to dispose predetermined transverse sections of the strip one upon the other to increase the depth of color of said markings on the resulting ribbon formed by folding said strip by arranging portions of said markings one upon the other.

11. The herein described method of forming characterized cellulosic ribbon which consists in providing an elongated strip of cellulosic material, applying characterized markings on the strip at longitudinally spaced intervals, then folding the strip longitudinally to dispose predetermined transverse sections of the strip one upon the other to increase the depth of color of said markings on the resulting ribbon formed by folding said strip by arranging portions of said markings one upon the other, and arranging the markings on longitudinal areas of the strip so as to produce in the folding of said strip, a varied number of transverse marked sections arranged one upon the other to produce on the resulting ribbon a shaded effect of the colored marking applied to said strip.

12. The herein described method of forming characterized cellulosic ribbon which consists in providing an elongated strip of cellulosic material, applying characterized markings on the strip at longitudinally spaced intervals and occupying part only of the transverse sections of said strip, then folding said strip to dispose one part of each

marked section upon another part of said marked section so as to produce on the resulting ribbon relatively deep color values in the markings as they appear longitudinally of said ribbon.

- 5 13. The herein described method of forming characterized cellulosic ribbon which consists in providing an elongated strip of cellulosic material, applying characterized markings on the strip at longitudinally spaced intervals and occupying 10 part only of the transverse sections of said strip, then folding said strip to dispose one part of each marked section upon another part of said marked section so as to produce on the resulting ribbon relatively deep color values in the markings

as they appear longitudinally of said ribbon, and changing the character or form of the markings on the resulting ribbon in the folding of said strip.

14. The herein described method of forming characterized cellulosic sheet material, which consists in applying characterized tint-like markings on predetermined sections or areas of a cellulosic sheet and in a color contrasting to the color of said sheet, and then folding the sheet to dispose a part of said markings upon other parts of said markings to produce in the resulting product markings of deep color value and of predetermined contour. 5

MORRIS KATZ.
